UNITED STATES PATENT OFFICE.

LOYD JOSHUA GAY, OF BROOKFIELD, GEORGIA.

LIFTING-JACK.

1,134,447.

Specification of Letters Patent. Patented Apr. 6, 1915.

Application filed April 10, 1914. Serial No. 831,029.

To all whom it may concern:

Be it known that I, LOYD J. GAY, a citizen of the United States of America, residing at Brookfield, in the county of Tift and

5 State of Georgia, have invented certain new and useful Improvements in Lifting-Jacks, of which the following is a specification.

This invention relates to lifting jacks and it has for its object the provision of an improved article of this nature constructed in such manner that a lifting lever may be moved bodily with relation to the standard of the jack to approximate working position, after which the swinging movement of 10 the lever is utilized to lift a vehicle wheel or other object, clear of the ground.

Further objects and advantages of the invention will be set forth in the detailed description which now follows.

20 In the accompanying drawing, Figure 1 is a side view of a jack constructed in accordance with the invention, Fig. 2 is a partial perspective view thereof, Fig. 3 is a partial front elevation thereof, and Fig. 4 is a partial rear elevation thereof.

Like numerals designate corresponding parts in all of the figures of the drawing.

Referring to the drawing the numeral 5 designates a standard that is supported 30 upon a foot or base, 6. The standard 5 is vertically and centrally slotted throughout substantially its entire length as indicated at 7 through which slot a lever 8 works. This lever is pivoted upon the pin 9 which 35 is supported in ears 10 of a head 11. This head is preferably formed of resilient sheet metal so that its lower portions comprise spring fingers 12 which fingers are adapted to have yielding engagement with relatively 40 long ratchet teeth 13 formed upon the front face of standard 5. The rear face of the standard is provided with ratchet teeth 14 which are reversely arranged with relation to teeth 13 and are much shorter to thereby

45 give a finer adjustment to the throw of lever 8 than is secured in getting the approximate position of head 11. The head 11 comprises the fingers 12 and the ears 10 and the extensions 15 which latter engage about the 50 said standard 5 to hold the head in sliding engagement therewith. A yoke shaped pawl 16 is pivotally connected with the lever 8 at 17 and as the rear or handle portion of the lever is drawn downwardly this pawl rides over the ratchet teeth 14 to hold the lever in any position to which it may be moved to

hold a load, such as a vehicle axle or wheel which rests upon the forward end 8' of the lever.

It is believed that the operation of the device will be apparent without further remarks however, it may be briefly stated that in use if it be desired to raise a vehicle wheel from the ground, the standard is disposed adjacent the part to be raised and the head 60 is moved bodily while the handle portion of the lever is in an elevated position to thereby bring the forward end 8' of the lever to an approximate engaging position with the part to be lifted. The head is held in this 65 position of preliminary adjustment by the engagement of the fingers 12 with the ratchet 13. When the handle end of the lever is forced downwardly the forward end 8' thereof moves upwardly lifting the part 70 engaged from the ground. At the same time the yoke pawl 16 rides over the ratchet teeth 75 14 in the manner above set forth.

While the elements shown and described are well adapted to serve the purposes for 80 which they are intended, it is to be understood that the invention is not limited to the precise construction set forth, but includes within its purview such changes as may be made within the scope of the ap- 85 pended claims.

Having described my invention, what I claim is:

1. In a lifting jack the combination with a standard having reversely arranged 90 ratchet teeth upon its opposite faces, of a head slidably engaging said standard said head being made of sheet metal and comprising integral spring fingers adapted to engage the ratchet teeth upon one face of 95 the standard, a lever pivoted to said head and a pawl carried by said lever for engaging the ratchet teeth upon the opposite face of the standard.

2. In a device of the character described, 100 the combination with a vertically arranged standard which is centrally slotted and which has reversely arranged ratchet teeth upon its opposite faces, of a sheet metal head slidably engaged with said standard 105 and comprising integral spring fingers adapted to engage the ratchet teeth upon one side of said standard, a lever pivoted to said head and a yoke shaped pawl pivoted to said lever and extending across said 110 standard to engage the ratchet teeth on both sides of the slotted portion of the standard.

3. In a device of the character described the combination with a vertically arranged standard which is centrally slotted and which has reversely arranged ratchet teeth upon its opposite faces, of a sheet metal head slidably mounted upon said standard and comprising integral spring fingers extending downwardly from its lower portion, which fingers are adapted to engage the ratchet teeth upon one side of said standard, a lever extending through the slotted portion of the standard and pivoted to said

head upon the side remote from said integral spring fingers, and a yoke-shaped pawl pivoted to said lever and extending across 15 said standard to engage the ratchet teeth on both sides of the slotted portion thereof.

In testimony whereof I affix my signature in presence of two witnesses.

LOYD JOSHUA GAY.
